UNITED STATES PATENT OFFICE.

RICHARD G. WOOD, OF CINCINNATI, OHIO.

BALLOT-BOX.

SPECIFICATION forming part of Letters Patent No. 387,572, dated August 7, 1883.

Application filed August 31, 1887. Serial No. 248,356. (No model.)

To all whom it may concern:

Be it known that I, RICHARD G. WOOD, a citizen of the United States, and a resident of Cincinnati, in the county of Hamilton and State 5 of Ohio, have invented certain new and useful Improvements in Ballot-Boxes, of which the following is a specification.

This invention is an improvement upon the ballot-box for which Letters Patent No. 10 340,069 were granted to me April 13, 1886.

It consists in novel means for so constructing the box that its contents are inaccessible from the outside to unauthorized persons.

It consists, also, in means whereby the ballot opening and the registering mechanism is locked so that a ballot cannot be inserted except at the proper time and in the proper manner.

It also consists in means whereby each ballot will in its passage into the box automatically 20 release the actuating mechanism which carries it, which mechanism will be again automatically locked after the ballot has passed until the next is introduced, thus effectually preventing false registration.

25 It consists, also, in certain other details of construction and combination of parts, all of which will be first fully described in connection with the accompanying drawings, and then particularly referred to and pointed out 30 in the claims.

Referring to the drawings, in which like parts are indicated by similar reference-letters wherever they occur throughout the various views, Figure 1 is a perspective view of my 35 registering ballot-box with the turret or head which contains the canceling and registering mechanism in the position it is to occupy when the ballots are being cast. Fig. 2 is a vertical section taken through line *x x*. Fig. 3 is 40 a plan view with the turret turned, as it should be after the close of election, to prevent the canceling or registering mechanism being injured or tampered with, as well as to prevent the further introduction of ballots. Fig. 4 is a transverse section of the box, showing the top 45 in inverted plan view with the registering and canceling mechanism removed. Fig. 5 is an edge elevation of the turret inverted. Fig. 6 is a detail view, in vertical section, of the form 50 of turret used for cheap or non registering and canceling boxes, illustrating a simple means for locking the ballot-opening after the elec-

tion is closed. Fig. 7 is an inverted plan view of the turret containing the mechanism for introducing the ballots, printing and canceling them, registering the number of the vote cast, and giving audible notice when each ballot is cast. Fig. 8 is a view in vertical section through the frame of the mechanism and crank-shaft on line *y y* of Fig. 7. This view shows 60 the mechanism in side elevation removed from the turret and in the position it occupies when a ballot is started into the box. Fig. 9 is a similar view of the mechanism after the ballot has been deposited and in position to receive 65 another. Fig. 10 is an edge elevation of the cam which operates the arm of the alarm, and Fig. 11 is an end elevation of the cam which actuates the register.

The top and bottom of the box are, for light- 70 ness, made of wood, having the grain arranged in opposite directions to prevent warping. They are each recessed to receive the metal-bound columns A, and grooved to receive the combination wire and glass sides B, the top 75 and bottom edges of which rest in these grooves, while the side edges rest in rabbets in the columns A. On the bottom, and parallel with grooves upon opposite sides, are secured across the grain of the wood two metal 80 bars, C, the opposite ends of which have square or non-circular openings to receive the square shanks of the cap-nuts c, which project through from beneath, the heads of the nuts serving as feet for the box. To the under 85 side of the top are also secured similar metal bars, C'. These are perforated at the ends, and the upper portions of the perforations counterbored to receive the heads of the bolts D, the lower screw-threaded ends of which, 90 entering the nuts c, clamp the sides and columns firmly between the top and bottom. The bolts have perforations d, to receive a key or pin for turning them to draw the parts together. The top of the box is provided with 95 handles E, the shanks of which project through it, and also through the plates C', and are screw-threaded to receive tightening-nuts e, which assist to hold the plates firmly to the top. The handles E are made to project up 100 above the top of the turret, so that after the election the boxes may be packed away, one on top of the other, without injury.

The top has a central opening to receive the

removable metal turret F. Through this opening the box is secured together by the bolts D, so that when the turret is locked in place it is impossible to enter the box or tamper with its contents without breaking it to pieces.

The turret F is a circular cast-metal shell. It has an outwardly-projecting flange, f, which rests upon the top of the box. The portion 10 below the flange snugly fits the circular opening in the top, and is perforated at f' to receive the bolts of the two combination-locks G and one or more Yale locks, H, which are secured to the under side of the top. The 15 lower edge of the turret has an outwardly-projecting lug, f'', and the edge of the opening in the top opposite the lock H is cut away to permit it to pass when the turret is placed in position. When the flange f rests upon the 20 top and is turned to either position shown in Figs. 1, 3, or 4, the lug f'' passes under the top and locks the turret in place. Some space is left between the top of the lug and the under side of the top to prevent binding, and it need 25 not fit closely when the turret is turned to the position shown in Figs. 3 and 4, as the bolts of the three locks can be depended upon for holding the turret; but when turned in the position shown in Fig. 1 the combination-locks 30 are not in use, the lug and Yale lock being depended upon. In order to hold the turret steady, I therefore provide a spring-plate, f'', under which the lug passes. This draws the flange f of the turret down firmly upon the 35 top, and holds it steady while the handle p is being turned during the voting. Two lugs, f' f'', project out from the flange f, to stop the turret in either position by coming in contact with a screw or pin. (Shown in dotted line, 40 Fig. 4.)

Referring to Sheet 2, J is an open cast metal box. It furnishes bearings for the mechanism which prints and cancels the ballots, conveys them into the box, actuates the register, 45 and sounds the alarm. The frame is secured to the top of the turret by screws passing through lugs at each end.

K K' are rolls covered with felt or some absorbent material for supplying the rubber-covered printing and canceling roll L with ink, and M is a rubber friction-roll in contact with roll L, for conveying the ballots into the box. The inking-rolls and the rolls L M do not differ from those shown in my said former 55 patent, except that I print a small circle concentric to the puncturing-point, so as to more easily detect false ballots should they be by any irregular means placed in the box.

N is a swinging frame pivoted upon the 60 journals of roll K. Its free end is held, when in its normal position, beneath the discharge of rolls L M by a spiral spring, n, one end of which is secured to a downwardly-projecting arm, n'', of frame N, and the opposite end is 65 secured on a pin or projection from frame J. The frame N has an upwardly-projecting stud, n', which, when the free end of the frame N

guards the passage from the rolls L M, bears upon the iron case of roll L, in the path of a pin, l, as seen clearly in Fig. 9. The object 70 of this is to block the rolls from turning unless a ballot is passing between them, and thus prevent false registration. The ballot O, Fig. 8, on its passage through the rolls, carries the frame downward, taking its stud n' out of the 75 path of the pin l, permitting the rolls to be revolved until the ballot is discharged into the box.

The roll L is secured upon the shaft P. It extends through the sides of frame J and 80 through the rim of turret F beyond the side of the box, and has secured upon its end a cross-head, P', one end of which is provided with a handle, p. The circumferences of the rolls M and L should be a little greater than 85 the length of the folded ballot, so as to insure the passage of one ballot by a single revolution of the rolls. For certainty of starting the ballot in at the proper point of the rolls, the cross head P' should be secured upon its 90 shaft in a plane nearly at right angles to the axis of the pin l. Thus the rolls being in proper position, as shown in Fig. 9, to receive a ballot into their bite, the handle p should be at its lowest position. Now, a ballot being 95 pressed into the bite of the rolls and the handle turned, the ballot will reach the position shown in Fig. 8, and, pushing down the frame N, carry the stud n' out of the path of pin l, and permit a complete revolution of the rolls, 100 which is indicated by the sound of bell Q. The frame N is prevented from moving too far by its arm n'' coming against a stop, n'', projecting down from the frame J, and after the pin l has passed the projection and the 105 leading end of the ballot passed the end of arm-frame N the frame is partially returned by a screw, l', striking a cam-plate, n', secured upon the frame N, so as to bring the stop n'' in the path of pin l and prevent the rapid revolution of the handle getting the pin l a second time past the stud before the spring could return to the frame N. This action, also being positive, obviates any danger from the weakening of the spring n.

Upon the inner end of shaft P is secured a cam-collar, R, the inner end of which is formed with the knocker-cam S, and the outer is formed with the eccentric T, which actuates the register U, which is of ordinary construction and secured to the top of the turret F by screws passing through the ends of a bar, u, secured upon the register-case. Upon one of the screws which secure the register to the turret is pivoted an arm, t, which carries at its 110 free end a shoe, which shoe bears upon the eccentric T and intervenes it and the push-rod u' of the register.

The knocker-arm Q' is pivoted upon a screw secured in the side of frame J, and has a shoe, q, projecting from one side, which rides over the notched cam S, with which it is held in contact by a spring, q', connected to an extension of the arm Q', and a stud-pin on the frame

J. The purpose of notching the cam S is to prevent the handle from being turned back after the ballot has been started between the rolls without carrying it through and indicating on the register that a ballot has been cast. It will thus be seen that the handle is locked from turning in either direction sufficiently to affect the register when no ballot is on its way into the box, and that it cannot be turned in the wrong direction sufficiently to affect the register at any time.

It will be noticed that the cross head P' is formed in the shape of the letter S or figure 8; but any shape that may be suggested by the taste of the constructor may be used. It is only necessary that the projection be sufficiently below the major axis of the cross head to rest upon the top of the box when the turret is turned and locked, as seen in Figs. 3 and 4, to prevent the handle from turning. This arrangement, in addition to preventing any interference with the mechanism, also prevents the shaft from being sprung or bent by accident or carelessness in storing the boxes after the returns are made.

The manner of using my registering and canceling ballot-box is as follows: The combination-locks being in the unlocked position, the turret turned to the position shown on Fig. 1, with the handle p in its lowest position, and the bolt of the Yale lock shot into one of the slots f' in the turret, and the register set at zero, a folded ballot being pressed into the bite of the rolls L M, the handle is turned once around, which is indicated by the alarm-bell Q. This operation carries the ballot into the box, prints and punctures it, and at the same time moves the register, indicating that one ballot has been cast. The same operation is performed with each ballot presented until the balloting is closed. When the count is to be made, the bolt of the Yale lock is retracted, the turret turned until the lug f' comes beneath the notch in the circular opening of the box, which position may be determined by the point of lug f' registering with a mark on top of the box. The turret is then lifted out and the ballots counted, to see if their number corresponds to the number of ballots cast, as indicated by the register. Should there be a surplus of ballots, they are then examined to detect the spurious ones, which can be readily done by noticing whether any have been wrongly punctured. After the ballots have been purged and the count completed they are returned to the box, (if the law so requires,) together with the returns, or a duplicate set of them made by the judges and clerks. The turret is then replaced, the handle turned to bring the major axis of the cross-head parallel with the top of the box, and the turret turned to the position shown in Figs. 3 and 4, after which the bolts of all the locks are shot into the perforations f', the tumblers of the combination-locks thrown by giving their arbors one or more turns, and the key removed and returned to the proper offi-

cer. While I have shown three locks on my box, it is evident that any number may be used.

In Fig. 6 I have shown my turret arranged for a cheap non-registering and non-canceling ballot-box. The only difference between the turret F and the one, F', here shown is that the top is lower and, for additional security, has an angle-lug, f", cast upon it alongside the ballot-opening, to receive the end of the angle-plate w, which is secured to the under side of the top and projects up against the top of the turret to lock the ballot opening when the turret is turned after the election is closed. By making the angle w of heavier material the lug f" may be dispensed with.

I have shown what I believe to be the best form of my invention; but it is obvious that certain structural changes may be made without departing from the spirit of my invention. For instance, the corner-pillars A may be omitted and the meeting edges of the sides joined together; or the sides may be a single piece molded or pressed to the proper form.

The peculiar registering and canceling mechanism shown is not claimed herein, as it is to be made the subject of a separate application.

I claim—

1. In a ballot-box, the combination of the top and bottom, grooved to receive the sides, the top having an opening to receive a removable turret, the removable turret fitting said opening, the plates C C', secured, respectively, to the top and bottom, the bolts D and nuts e, for securing the box together, and one or more locks for securing the turret in place, substantially as shown and described.

2. The combination, substantially as specified, of a ballot-box secured together from the inside and having an opening for access to the interior, with a removable turret adapted to be secured in and to close said opening, and one or more locks to secure the turret against removal.

3. The combination of a ballot-box secured together from the inside and having a circular opening to receive a removable and rotary turret, the turret adapted to enter and close said opening, and having its side perforated to receive lock-bolts, the lock or locks secured to the under side of the top in a position to lock the turret in position to receive the ballots, or in the position shown after the ballots are cast to lock the ballot-opening, substantially as shown and described.

4. The combination, substantially as specified, of the grooved top and bottom, having in addition to the grooves depressions to receive the columns A, the glass sides B, the metal plates C C', bolts D and non-rotatable nuts e, for securing the box together, the removable turret, and the locks for securing the turret in the top-opening.

5. The combination of the top and bottom, grooved and recessed as shown, the glass sides and metal-bound columns, the plates C C',

bolts D and nuts e, for securing the box together, the removable turret, and locks for securing the same in the opening, substantially as hereinbefore set forth.

5 6. The combination, substantially as specified, of the top and bottom, grooved, as set forth, to receive the sides, the plates C C', bolts D and nuts e, for securing the same together, the handles E, passing through the top, 10 and plates C', and the nuts e, for securing the handles and assisting to secure the plates C' to the top, with the removable turret and locks for securing it in place.

7. The combination of a ballot box secured 15 together from the inside and having a circular opening in the top, the turret F, having a flange, f, to rest upon the top of said box, and perforated rim below said flange to enter said opening, locks secured to the under side of 20 said top in a position to have their bolts shot into said perforations, registering mechanism secured within said turret and having an actuating-shaft projecting through said turret and

beyond the side of said box, and a cross-head secured upon said shaft, to rotate it when 25 turned with the turret parallel with the side of the box, and to bear upon the top of the box and prevent rotation of the shaft when the turret is turned to bring said shaft diagonal to the box-top, and locks to hold the turret in 30 either position, substantially as specified.

8. The combination of the ballot-box having a circular opening in the top, the turret F, fitted to turn in said opening, the plate w, secured to the under side of the box and projecting beyond the ballot-opening in the turret, to uncover or cover said opening as the turret is turned in one or the other position, and a lock or locks to hold the turret in either position, substantially as and for the purpose 40 set forth.

RICHARD G. WOOD.
